MULTIPLE COMPARTMENT VENDING MACHINE

John B. Brock, Adairsville, Ga.

Application September 8, 1947, Serial No. 772,857

18 Claims. (Cl. 312—48)

1 This invention relates to a machine for refrigerating and cooling and dispensing bottled beverages and comprises a cabinet having a plurality of vertically disposed compartments with dispensing means disposed at the lower end of the compartments and coin controlled means for moving the dispensing means successively so as to deliver one bottle from one column upon one operation of the machine and upon the next operation to deliver a bottle from the next adjacent column or any other column and so on until the cycle is completed at which time the delivery of the bottles is repeated, first from one column and then the next adjacent or any other column.

It is an object of this invention to provide a vending machine having means for storing and refrigerating a plurality of vertically disposed columns of bottled beverages, articles of merchandise and the like, with means for supporting the lowermost portions of the columns of bottles, and means for successively operating the supporting means to allow one bottle at a time to drop from one of the columns and to support the other bottles in all other columns including the column from which a bottle has been dispensed against moving out of the respective column.

It is another object of this invention to provide a vending machine for vending bottled beverages comprising a cabinet having a plurality of vertically disposed partitions therein, dividing the cabinet into a plurality of vertically disposed compartments with cam means disposed below each one of the compartments and interconnected with each other together with actuating means for simultaneously actuating all of the cam means to allow one bottle from one compartment to be dispensed upon an operation of the cam means and successive operations of the cam means allowing another bottle to be dispensed from another compartment until all of the compartments have had their lowermost bottle dispensed therefrom at which time the cycle is repeated.

It is another object of this invention to provide in a vending machine for articles of merchandise, such as bottled beverages, means for storing a plurality of columns of bottled beverages, means for dispensing a bottle at a time from one of the columns at a time, said machine having an exit opening with means for closing the opening together with a second means for closing the opening, and check controlled apparatus adapted to move the second closure means from over the opening and to rotate the first closure

2 means in the opening to deliver a bottle from the interior of the cabinet while the second means are moved to non-closing position, both of said closure means being adapted to automatically return to closing position to thereby form a double closure for the exit opening or delivery opening of the machine and thus prevent unauthorized tampering with the mechanism and also prevent the ingress and egress of air to the interior of the compartment which is usually refrigerated.

Some of the objects of the invention having been stated, other objects will appear as the description proceeds when taken in connection with the accompanying drawings, in which

Figure 1 is an isometric view of the vending machine;

Figure 2 is an elevation looking at the front side of the machine with the front door removed;

Figure 3 is a sectional view taken substantially along the line 3—3 in Figure 2;

Figure 4 is a vertical sectional view taken along line 4—4 in Figure 3;

Figure 5 is a vertical sectional view taken along the line 5—5 in Figure 2;

Figure 6 is an elevation with parts in section and taken along the line 6—6 in Figure 2;

Figure 7 is an enlarged detail view of the lower right-hand portion of Figure 2;

Figure 8 is an isometric view of a portion of the parts shown in the lower portion of Figure 7;

Figure 9 is a vertical sectional view taken along the line 9—9 in Figure 7;

Figure 10 is a vertical sectional view taken along the line 10—10 in Figure 7;

Figure 11 is a vertical sectional view taken along the line 11—11 in Figure 9 with parts omitted.

10 Referring more specifically to the drawings, the numeral 10 indicates a suitable cabinet having a merchandise compartment formed from top insulated wall 11, bottom insulated wall 12, insulated side walls 13 and 14, insulated rear wall 15 and an insulated front door 16 hinged as at 17. To the right side of side wall 13 in Figures 1 and 2 suitable noninsulated walls 20 and 21 are formed integral with the cabinet but the front side thereof is closed by the free end portion of door 16. This compartment is indicated broadly at 19 and it also has a top wall 23. Disposed between the insulated side wall 13 and the outer wall 21 is a forwardly sloping troughlike member 24, which extends out through the lower front wall 25 and has a lip portion 26 which pre-

vents a bottle from passing entirely out of the trough 24.

The cabinet has a suitable bottom or base portion 27 to which the side walls and rear wall are joined for support. This forms a compartment 28 for housing the motor and compressor to be later described.

A suitable frame is secured within the lower portion of the upper compartment 30 and this frame comprises any suitable structure such as a piece of strap iron comprising a portion 31 secured to and extending from the inner surface of side wall 13 across and suitably secured to the inner side wall surface 14 as at 33 and extends a short distance along this inner surface of side wall 14 and then a portion 32 projects parallel to the leg 31 back to the inner surface of side wall 13 and then portion 33 extends along and is secured to the inner surface of side wall 13 to where it joins the inner surface of rear wall 15, the portion 34 being slightly spaced from the inner surface of rear wall 15 and being spotted as at 35 and 36 to the inner lining of the cabinet. The rear wall has an offset undercut portion as at 37 to make space for this portion 34. Rotatably mounted in the members 32 and 34 are shafts 40, 41, 42, 43, 44, 45 and 46, having on the front ends thereof, and fixedly secured thereto, and disposed between the members 31 and 32, pinions 50, 51, 52, 53, 54, 55 and 56.

Rotatably mounted on suitable stud shafts 60, 61, 62, 63, 64 and 65 mounted in and disposed between the members 31 and 32 are the idler gears 70, 71, 72, 73, 74 and 75 which mesh with the pinions of gears 50 to 56 inclusive, mounted on the ends of the shafts 40 to 46 inclusive.

Spanning the distance between the members 32 and 34 are strap iron members 80, 81, 82, 83, 84, 85 and 86. Slidably fitted over these strap iron members 80 to 86 inclusive, are fittings 90, 91, 92, 93, 94, 95 and 96, there being two of these fittings 90 to 96 inclusive for each of the cross bars 80 to 86 inclusive as is evident in Figure 3. The lower ends of these fittings 90 to 96 inclusive are slotted to fit over the bars 80 to 86 inclusive, and the lower ends of the members 90 to 96 inclusive have an enlarged slot for fitting over and down onto the shafts 40 to 46 inclusive.

Bars 32 and 34 are notched for receiving outwardly projecting portions on the bars 80 to 86 inclusive as is evident in Figure 5. After the fittings or members 90 to 96 inclusive are inserted in place on the bars 80 to 86 inclusive, then suitable partitions 100, 101, 102, 103, 104, 105 and 106 respectively have their lower ends suitably secured or slid into slots in the upper ends of members 90 to 96 inclusive and these partitions 100 to 106 inclusive extend upward to and are suitably secured to the lower surface of the top wall 11 and may also be suitably secured to the inner surface of back wall 15. The partition 106 extends forwardly for a greater distance than the other partitions and has a resilient gasket 107 against which the inner surface of door 16 fits.

The upper ends of the partitions 100 to 106 inclusive are perforated by any suitable means such as a plurality of vertically disposed slots 109 for ventilation purposes to be later described. The partitions 100 to 106 inclusive form vertically disposed compartments 110, 111, 112, 113, 114 and 115 into which bottled beverages can be stacked in a prone or flat position.

Disposed in spaced relation to the bars 31, 32 and 33 and extending from the back wall 15 to flush against the inner surface of the door 16 is

a sloping plate member 120 which also spans the distance and is secured to the inner surfaces of the walls 13, 14 and 15. Plate 120 has a gasket 116 on its front edge against which the inner surface of door 16 fits. Plate 120 also has a large opening 118 in its left hand end in Figures 3 and 4 through which air is forced by the fan, to be presently described.

Plate 120 is substantially parallel to but is in spaced relation to and disposed below the bars 31, 32 and 34. This plate 120 has a plurality of perforations 117 therein through which the air is drawn downwardly through the vertical compartments 110 to 115 inclusive. The holes 117 increase in size from left to right in Figure 3 to cause proper ventilation as will be later explained.

Disposed below this sheet metal partition 120 is an electric motor 121 mounted on a suitable motor mount 122 supported on the upper surface of bottom portion 12. The motor 121 has on its shaft a fan 123 which is mounted in a suitable opening 124 in a sheet metal member 125 which extends from the bottom 12 up past the sheet metal partition 120 and against the partition 106 (see Figure 2) and it also extends from the inner surface of the back wall flush against the inner surface but not secured to the inner surface of the front door 16, but has a gasket 119 on its front edge against which front door 16 fits. This will cause the air to be drawn downwardly through the compartments 110 to 115 inclusive and through the openings 117 and through opening 124 and upwardly in the space 130 occurring between the partition 106 and the inner surface of the side wall 14.

Disposed in the space 130 is a refrigerating coil 126 which is connected to a suitable compressor 127 disposed in the lower portion 28 of the cabinet 10 and driven by a suitable electric motor 128 through the medium of any suitable means such as a belt 129. In front of the discharge side of the fan 123 is provided a curved vane 131 for directing the blasts of air upwardly through the passageway 130.

One of the pipes leading from the compressor has a conventional expansion valve 132 therein and a suitable thermostatic switch 133 is provided which is wired by means of wires 134 and 135 to the wires 136 and 137 leading to the electric motor 128 whereby the motor will be cut on and off as desired to maintain the desired temperature within the interior of the cabinet 10.

The fan 121 has suitable wires 138 and 139 leading therefrom to a suitable source of electrical energy and this fan is usually driven continuously while the apparatus is in operation.

Each of the shafts 40 to 46 inclusive has cams 140 to 146 inclusive thereon, there being two cams on each shaft set at the same angularity. These cams are for supporting and dispensing the bottled beverages disposed within the vertical chutes or compartments 110 to 115.

A shaft 150 extends through both of the bars 32 and 31 just below shaft 41 and is held laterally secure by collars 224 and 225 and on the front side of the bar 31 has fixed thereto a pair of spaced disks 147 and 148 held in spaced relation to each other by suitable spacer members 151, 152, and 153. The outer disk or front disk 148 has a triangular cut away portion 155 therein which has at each corner thereof cavities 156, 157 and 158. The stud shaft 150 has fixed thereon a pinion 226 which is one-half the diameter of the pinion 51 fixed on the shaft 41, and pinions 225

and 51 are in engagement with each other at all times.

A pin 160 is adapted to rest one at a time in these cavities 156, 157 and 158, said pin being in one end of a link 161 which is offset as at 162 and is pivotally secured as at 163 to an end disk or circular portion 165 of a trough member 164. The trough member has also its other end of circular formation and indicated at 166 and extending between the circular head members 165 and 166 is a semi-circular trough portion 167. The head members 165 and 166 have extending therefrom stud shafts 170 and 171 respectively, the shaft 171 being mounted in a suitable opening in the inner lining of rear wall 15 and this lining for side wall 15 extends across and forms a lining for the bottom member 12. A bearing 174 is provided on bottom 12 for reception of the shaft 170 so that shafts 171 and 170 can oscillate in said bearings. In the door 16 is mounted a suitable lock 175 and a suitable coin return member 176 and a coin slot 177 and a bottle opener 172.

The coin slot 177 leads into a conventional slug rejector 180 and which forms no part of the present invention. This portion 180 is supported by a suitable bracket 181 secured to the exterior of side wall 13.

The slug detector mechanism which is conventional and is not described and which is housed within housing 180 has extending therefrom a chute 178 which leads to the exterior of the machine to deliver a slug or rejected coin to the receptacle 176 shown in Figure 1. This housing 180 also has a coin chute 179 through which accepted coins will fall into the coin trough 195.

Mounted on the exterior of the wall 13 is a bracket 182 which has a pivot pin 183 therein on which is pivoted a bell crank 184 having three legs 185, 186 and 187. Integral with bell crank 184 is an upwardly projecting portion 190 having an elongated slot therein penetrated by a pin 191 extending from the exterior of wall 13 so that member 190 can slide relative to the pin 191. A compression spring 192 surrounds the pin 191 and thumb nuts 194 are mounted on the pin or bolt 191 for regulating the tension in the compression spring 192.

The portion 187 of the bell crank 184 has a coin trough 195 fixed thereto into which the coin if it passes the test in housing 180 will drop. The added weight of the coin will overbalance the bell crank 184 and cause it to move in a clockwise manner in Figure 2 or to the position shown in Figure 7, and arm 186 has a projection 197 thereon which will engage a micro-switch button 198 in a housing 199 to complete a circuit as wires 200 and 201 leading from a suitable source of current pass into the housing 199 and wires 202 and 203 lead out of the housing 199 to cause a circuit to flow through a coil 205 which will energize a solenoid core 206 whose lower end is connected to a gate 208 slidably mounted in slides 209 and 210. The gate along with the semi-circular portion 167 serves as a double closure for the exit portion of the compartment in which the bottled drinks are stored. The gate has extending therefrom a projection 212 having a slot 213 therein loosely fitting over a pin 214 fixed in cylindrical head member 165.

While the coin is rolling down the coin trough 195 the micro-switch will remain closed to cause the gate 208 to be raised which will also move the semi-circular trough portion 167 an approximate half revolution, which will allow the lowermost bottle therein to roll out of the open-

ing 215 normally closed by the gate 208 and when the coin in coin trough 195 has dropped into a coin box 217 the bell crank 184, under impetus of compression spring 192 will move to normal position or to the position shown in Figure 2 and de-energize the solenoid coil 205 and allow the gate to move by gravity to closed position and the parts will assume the position shown in Figure 2.

Method of Operation

It will be noted that each one of the shafts 40 to 46 inclusive has two cams 140 to 146 fixed thereon, and due to the fact that pinion 226 has one-half the diameter of pinion 51, and due to the fact that stud shaft 150 is moved one-third of a revolution for the delivery of each bottle, then it is quite evident that the cam shafts 40 to 46 will be rotated one-sixth of a revolution for each delivery of a bottle from the machine.

When a coin which is accepted and has passed into the machine and closed the micro-switch 199 by pressure on button 198 to energize the solenoid 205, then the trough member 164 will be rotated slightly less than one-half a revolution, and this will move the parts from the position shown in Figure 2 to the position shown in Figure 7.

There will always be a bottle ready for delivery resting against the concave surface of portion 167, ready for delivery. The movement of the trough member 164 from position shown in Figures 2 and 4 to the position shown in Figure 7 will impart a one-sixth revolution to all of the cam shafts 40 to 46 inclusive with the cams thereon.

It will be noted that with the parts in the position shown in Figure 4 that the bottle is resting inside the trough portion 167 ready for delivery and when the cams are moved the bottle supported by the trailing end of cam 141 will be allowed to fall downwardly. Upon energization of the solenoid coil 205, the gate 208 will be lifted and the upward movement of the gate will cause the trough member 164 to be rotated slightly less than a half a revolution until its lip 167a will engage the sheet metal member 120 and this will allow the bottle contained within the trough portion 167 to be delivered to the exterior of the machine and fall into the chute or trough 24 to slide to the exterior of the machine. By the lifting of the gate 208 and movement of the parts to the position shown in Figure 7, then the cams 149 to 146 will be moved one-sixth of a revolution in a clockwise manner and this will move the trailing end of cam 141 from beneath the bottle supported thereby and allow this bottle to fall downwardly onto the sheet metal member 120, to roll down to the position shown in Figure 7 against the outer peripheral surface of the trough portion 167. Now, the weight of the gate, when the coin has rolled out of the trough 195, breaking the circuit to the solenoid coil 205 will cause the gate to move to closed position which will move the trough member 164 to the position shown in Figures 2 and 4 and will cause the link 161 to slide backwardly and fall into the next succeeding notch, such as 151 in Figure 8 in the triangular cavity 155 ready for a subsequent operation. Upon the next operation, then, of course, cam 142 will be moved far enough to allow the lowermost bottle in its associated column to the left-hand thereof in Figure 4 to fall downwardly onto the plate 120. Of course, in the beginning of operation in all probability the machine would be set so that the bottle which is

shown ready for delivery in Figure 4 would have been released by the cam 140 and at the same time, the leading edge of cam 141 will move in below the next succeeding bottle thereabove. This happens throughout the sequence as to cams 140 to 146 and then the sequence starts over again, it being understood that as the trailing edge of two cams moves from beneath a bottle to allow it to fall, the leading edge of the next adjacent cams to the left will move beneath the bottle thereabove and support it to prevent its falling downwardly.

In the drawings and specification there has been set forth a preferred embodiment of the invention, and although specific terms are employed, they are used in a generic and descriptive sense only, and not for purposes of limitation, the scope of the invention being defined in the claims.

I claim:

1. A vending machine comprising a cabinet having a plurality of spaced partitions forming a plurality of compartments and a rotatable shaft mounted at the lower ends of each of the partitions, each shaft having thereon cam means for supporting horizontally disposed articles in said compartments and for vending one of the articles at a time from the compartments, means for moving all of the shafts simultaneously a partial revolution to cause the cam means on two adjacent shafts to release the lowermost article from one compartment and to engage the next article thereabove with the cam means on one of the shafts to prevent its passing out of its compartment, and upon the next operation of the machine moving two adjacent shafts to cause their cam means to release the lowermost article in another compartment and preventing downward movement of next to the lowermost article in the compartment, a sloping shelf disposed below all of the compartments onto which the articles are adapted to fall when released from a compartment, said cabinet having an opening at the lower end of said shelf through which the articles are adapted to pass to the exterior of the machine, a door closing said opening, a substantially trough-like member mounted in said opening and against which the articles are adapted to roll when released from one of the compartments, means for moving the door from over the opening and simultaneously partially rotating the trough-like member to allow an article resting therein to pass through said opening to the exterior of the machine and whereby the next article will roll against the convex portion of the trough-like member when released and be arrested against movement out of the opening, and a connection between the trough-like member and the means for moving the shafts for imparting a partial rotation to the shafts upon each movement of the door and trough-like member.

2. In a vending machine having a cabinet provided with a plurality of spaced partitions forming a plurality of compartments, a shaft rotatably mounted at the lower ends of the partitions, each shaft having thereon cam means for engaging and supporting two sides of the lowermost of a stack of articles thereabove, means for simultaneously imparting a partial revolution to all of said shafts to progressively move the same to allow the lowermost article in one compartment to be released therefrom to move to the exterior of the machine and to engage and hold the next lowermost article against downward

movement out of a compartment, the various shafts being movable in succession until all of the compartments have each delivered an article from the lower end thereof, said cabinet having a sloping shelf member disposed below the lower ends of the compartments onto which the articles released from a compartment are adapted to fall to roll to one side of the compartment, said cabinet having an opening in one side of the compartment at the lowermost end of the sloping shelf member, closure means for normally closing the opening, means for moving the closure means from over said opening to allow an article released from one of the compartments to roll through said opening to the exterior of the machine, and means for connecting the closure means to the means for imparting rotation to the shafts, whereby moving of the closure means to open position will impart a partial rotation to the shafts.

3. In a vending machine for bottled beverages, a cabinet having a plurality of spaced partitions forming a plurality of compartments therein in which bottled beverages may be stored in superposed relation, a plurality of rotatable shafts mounted near the lower ends of said partitions and each having cam means thereon for supporting columns of bottles in two adjacent compartments, a sloping shelf member disposed below the lower ends of the compartments and in spaced relation thereto and onto which a bottle released from a compartment may fall to roll to one side of the cabinet, said cabinet having an opening in one of its walls adjacent the lowermost point of said sloping shelf, a vertically slidable door normally closing said opening, a solenoid member connected to said door for raising the same, a concavo-convex oscillatable member mounted adjacent said opening for arresting the bottles rolling down the shelf, a connection between the door and the concavo-convex member, means operable by the closing of a circuit to said solenoid member for raising said door and oscillating said concavo-convex member to deliver a bottle through said opening to the exterior of the machine, and means connected to said concavo-convex member and to all of said shafts for simultaneously imparting a partial revolution to the shafts upon oscillation of the concavo-convex member and whereby upon delivery of a bottle through said opening to the exterior of the machine upon oscillation of the concavo-convex member, all of said shafts will be rotated to cause the cams on two adjacent shafts to release a lowermost bottle in one of the compartments to allow it to fall onto the sloping shelf and to roll against the concave side of said concavo-convex member.

4. In a vending machine for bottled beverages, a cabinet, a plurality of spaced partitions in said cabinet forming a plurality of compartments into which bottled beverages and the like may be placed in superposed relation, a plurality of rotatable shafts mounted at the lower ends of the partitions and geared together for simultaneous rotation, said cabinet having an opening in one side thereof and a sloping shelf having its lower end coinciding with the lower edge of said opening, said sloping shelf being disposed in spaced relation below the said rotatable shafts, a door for said opening, a solenoid coil connected to said door for raising the same to allow a bottle to roll from said shelf through said opening, means operable upon closing of a circuit for raising said door, a connection between said door and said

rotatable shaft to impart simultaneous rotation to all of the shafts upon raising of said door, each of said shafts having cams thereon and the cams being pitched at different angles on each of the shafts, said cams being arranged to support a column of bottles in each of said compartments and upon a partial revolution of all of the cams, the cams on two adjacent shafts permitting a bottle to drop from a compartment and the cams on one of the shafts having another portion for engaging the bottle thereabove for preventing its downward movement.

5. A vending machine comprising a cabinet having a plurality of spaced partitions therein forming a plurality of compartments, into which articles may be placed in superposed relation in a horizontal position, a shaft mounted at the lower end of each of said partitions, and each shaft having a pair of cams thereon with projections extending below two adjacent compartments for supporting and releasing the bottles in the compartments, all of said shafts being geared together for simultaneous rotation, means on the exterior of the cabinet and connected to said shafts for imparting simultaneous rotation to the same to impart a partial rotation to all of the shafts to so position the cams on two adjacent shafts to allow the lowermost article in one of the compartments to fall downwardly and to roll towards the exterior of the machine.

6. In a vending machine having a cabinet in which there is disposed a plurality of spaced partitions forming compartments, a plurality of rotatable shafts mounted between the lower ends of the compartments, means connecting all of the shafts together for simultaneous rotation, said cabinet having an opening therein through which articles are adapted to be delivered, the articles being adapted to be stacked in superposed relation in said compartments, each of said shafts having cam means thereon for preventing downward movement of the articles disposed with the compartment, but upon rotation of all of the shafts, the cams on one of the shafts serving to release the lowermost article in one of the compartments and the cams on an adjacent shaft also passing below the next lowermost article in that compartment to prevent its falling from the compartment.

7. A vending machine comprising a cabinet having a plurality of side by side compartments and a rotatable shaft mounted at each side of the lower ends of the compartments and between adjacent compartments, each shaft having thereon cam means for supporting horizontally disposed articles in said compartments and for vending one of the articles at a time from the compartments, means for moving all of the shafts simultaneously to cause the cam means on one shaft to release the lowermost article from one compartment and to cause the cam means on the other side of the compartment to engage the next article thereabove to prevent its passing out of its compartment, and upon the next operation of the machine causing another pair of shafts to release the lowermost article in another compartment and preventing downward movement of next to the lowermost article in the compartment, a sloping shelf disposed below all of the compartments onto which the articles are adapted to fall when released from a compartment, said cabinet having an opening at the lower end of said shelf through which the articles are adapted to pass to the exterior of the

machine, a door closing said opening, a substantially trough-like member mounted in said opening and against which the articles are adapted to roll when released from one of the compartments,

5 means for moving the door from over the opening and simultaneously moving the trough-like member to allow an article resting therein to pass through said opening to the exterior of the machine and whereby the next article will roll against the convex portion of the trough-like member when released and be arrested against movement out of the opening, and a connection between the trough-like member and the means for moving the shafts for imparting

10 a partial rotation to the shafts upon each movement of the door and trough-like member, a trough member disposed outside the opening through which the articles are adapted to pass and extending forwardly an opening in the front

20 of the cabinet adjacent the lowermost end of said trough and whereby an article when delivered to said opening will slide downwardly on said trough and through the opening in the front of the cabinet to where it can be seized by an

25 operator to remove it from the interior of the cabinet.

8. In a vending machine having a cabinet provided with a plurality of spaced partitions forming a plurality of compartments, a shaft rotatably mounted between each of the compartments and at the lower ends of the compartments and at the outer sides of the two outermost compartments, each shaft having thereon cam means for engaging and supporting a stack of articles thereabove, means for simultaneously imparting a partial revolution to all of said shafts to progressively move the same to allow the lowermost article in one compartment to be released therefrom to move to the exterior of the machine and to engage and hold the next lowermost article against downward movement out of a compartment, the various shafts being movable in succession until all of the compartments have each

30 delivered an article from the lower end thereof, said cabinet having a sloping shelf member disposed below the lower ends of the compartments onto which the articles released from a compartment are adapted to fall to roll to one side of

35 the compartment, said cabinet having an opening in one side of the compartment at the lowermost end of the sloping shelf member, closure means for normally closing the opening, and means for moving the closure means from over

40 said opening to allow an article released from one of the compartments to roll through said opening to the exterior of the machine, means connecting the closure moving means to the

45 means for imparting a partial revolution to the shafts, whereby the means for moving the closure means when operated will also impart a partial rotation to the shafts, a trough member disposed outside the opening through which the

50 articles are adapted to pass and extending forwardly an opening in the front of the cabinet adjacent the lowermost end of said trough and whereby an article when delivered to said opening will slide downwardly on said trough and through the opening in the front of the cabinet to where it can be seized by an operator to remove it from the interior of the cabinet.

9. In a vending machine for bottled beverages, a cabinet having a plurality of vertically disposed partitions therein forming compartments in

11

which bottled beverages may be stored in superposed relation, a plurality of rotatable shafts mounted near the lower ends of said partitions and each having cam means thereon for supporting columns of bottles in two adjacent compartments, a sloping shelf member disposed below the lower ends of the compartments and in spaced relation thereto and onto which a bottle released from a compartment may fall to roll to one side of the cabinet, said cabinet having an opening in one of its walls adjacent the lowermost point of said sloping shelf, a vertically slidable door normally closing said opening, a solenoid member connected to said door for raising the same, a concavo-convex oscillatable member mounted adjacent said opening for arresting the bottles rolling down the shelf, a connection between the door and the concavo-convex member whereby upon the closing of a circuit to said solenoid member said door will be raised and oscillating said concavo-convex member will be oscillated to deliver a bottle through said opening to the exterior of the machine, and means connected to said concavo-convex member and to all of said shafts for simultaneously imparting a partial revolution to the shafts upon oscillation of the concavo-convex member and whereby upon delivery of a bottle through said opening to the exterior of the machine upon oscillation of the concavo-convex member, all of said shafts will be rotated to cause the cams on one of the shafts to release a lowermost bottle in one of the compartments to allow it to fall onto the sloping shelf and to roll against the convex side of said concavo-convex member, a trough member disposed outside the opening through which the articles are adapted to pass, said cabinet having an opening in the front side thereof adjacent the lowermost end of said trough, and whereby an article when delivered to said opening will slide downwardly on said trough and through the opening in the front of the cabinet to where it can be seized by an operator to remove it from the interior of the cabinet.

10. In a vending machine for bottled beverages, a cabinet, a plurality of vertically disposed spaced partitions in said cabinet and forming compartments into which bottled beverages and the like may be placed in superposed relation, a plurality of rotatable shafts mounted adjacent the lower ends of the compartments and geared together for simultaneous rotation, there being a shaft on each side of each compartment, said cabinet having an opening in one side thereof and a sloping shelf having its lower end coinciding with the lower edge of said opening, said sloping shelf being disposed in spaced relation below the said rotatable shafts, a door for said opening, a solenoid coil connected to said door for raising the same to allow a bottle to roll from said shelf through said opening, means operable upon closing of a circuit for raising said door, a connection between said door and said rotatable shafts to impart simultaneous rotation to all of the shafts upon raising of said door, each of said shafts having cams thereon and the cams being pitched at different angles on each of the shafts, said cams being arranged to support a column of bottles in each of said compartments and upon a partial revolution of all of the cams, the shafts on one of the cams permitting a bottle to drop from a compartment and having another portion on a cam on an adjacent shaft for engaging the bottle thereabove for preventing its downward

75

12

movement and whereby a bottle released from a compartment will roll towards the exterior of the compartment while the door is in raised position, a trough member disposed outside the opening through which the articles are adapted to pass and extending forwardly, an opening in the front of the cabinet adjacent the lowermost end of said trough and whereby an article when delivered to said opening will slide downwardly on said trough and through the opening in the front of the cabinet to where it can be seized by an operator to remove it from the interior of the cabinet.

11. A vending machine comprising a cabinet having a plurality of vertically disposed partitions therein forming a plurality of vertically disposed compartments, into which articles may be placed in superposed relation in a horizontal position, a plurality of shafts mounted at the lower end of said compartments, there being a shaft at the lower end of each of said partitions and each shaft having a pair of cams thereon for supporting and releasing the bottles in the compartments, all of said shafts being geared together for simultaneous rotation, means on the exterior of the cabinet and connected to said shafts for imparting simultaneous rotation to the same to impart a partial rotation to all of the shafts to thus allow the lowermost article in one of the compartments to fall downwardly and means directing a released bottle to roll towards the exterior of the machine, said cabinet having an opening in one side thereof, a trough member disposed outside the opening through which the articles are adapted to pass and extending forwardly, an opening in the front of the cabinet adjacent the lowermost end of said trough and whereby an article when delivered through said first opening will slide downwardly on said trough and through the opening in the front of the cabinet to where it can be seized by an operator to remove it from the interior of the cabinet.

12. In a vending machine having a cabinet provided with a plurality of vertically disposed compartments disposed within a suitable cabinet and a plurality of rotatable shafts, there being a shaft mounted adjacent each side of and at the lower end of the compartments, means connecting all of the shafts together for simultaneous rotation, said cabinet having an opening therein through which articles are adapted to be delivered, the articles being adapted to be stacked in superposed relation in said compartments, each of said shafts having cam means thereon for preventing downward movement of the articles disposed within the compartments, but upon rotation of all of the shafts, the cams on one of the shafts serving to release the lowermost article in one of the compartments and the cams on an adjacent shaft also passing below the next lowermost article in that compartment, a trough member disposed outside the opening through which the articles are adapted to pass and extending forwardly, an opening in the front of the cabinet adjacent the lowermost end of said trough and whereby an article when delivered to said first opening will slide downwardly on said trough and through the opening in the front of the cabinet to where it can be seized by an operator to remove it from the interior of the cabinet.

13. A vending machine comprising a cabinet having an opening and having a plurality of vertically disposed spaced partitions forming compartments and a rotatable shaft mounted at the lower ends of each of the partitions and between adjacent compartments, each shaft having there-

on cam means for supporting horizontally disposed articles in said compartments and for vending one of the articles at a time from the compartments, all of the shafts being movable simultaneously to release the lowermost article from one compartment and to engage the next article thereabove to prevent its passing out of its compartment, and upon the next operation of the machine moving the shafts to cause another shaft to release the lowermost article in another compartment and preventing movement of next to the lowermost article in the compartment, a sloping shelf disposed below all of the compartments onto which the articles are adapted to pass to the exterior of the machine, a door closing said opening and against which the articles are adapted to roll when released from one of the compartments, means connecting the door to the trough-like member, means connecting the trough-like member to the shafts and means for moving the door from over the opening to simultaneously move the trough-like member and the shafts to release an article from a compartment and to allow an article resting in the trough-like member to pass through said opening to the exterior of the machine and whereby the next article released will roll against the convex portion of the trough-like member and be arrested against movement out of the opening.

14. A vending machine having a cabinet provided with a plurality of vertically disposed spaced partitions forming a plurality of vertically disposed compartments, a sloping shelf disposed below and in spaced relation to the lower ends of the partitions, a shaft rotatably mounted at the lower end of each partition, each shaft having thereon cam means for engaging and supporting the stack of articles thereabove, means for simultaneously imparting a partial revolution to all of said shafts to progressively move the same to cause the cam means to allow the lowermost articles in one compartment to be released therefrom to cause the cam means on the other side of the compartment to engage and hold the next lowermost article against downward movement out of a compartment, the various shafts being movable in succession until all of the compartments have each delivered an article from the lower end thereof, the released articles being adapted to fall onto said sloping shelf and to roll to one side of the compartment, said cabinet having an opening in one side of the compartment at the lowermost end of the sloping shelf member, closure means normally closing the opening, and means for moving the closure from over said opening to allow an article resting on said shelf to roll through said opening to the exterior of the machine, and means for connecting the closure moving means to the means for moving the shafts, so that opening of the closure will impart rotation to the shafts.

15. In a vending machine for bottled beverages, a cabinet having a plurality of spaced partitions therein forming compartments therebetween in which bottled beverages may be stored in superposed relation, each of said partitions having a lower end and an upper end, a plurality of rotatable shafts mounted near the lower ends of said partitions and each having cam means thereon projecting into the compartments for supporting a column of bottles in each compartment, a sloping shelf member disposed below the lower ends of the compartments and in spaced relation thereto and onto which a bottle released from a compartment may fall to roll to one side of the cabi-

net, said cabinet having an opening in one of its walls adjacent the lowermost point of said sloping shelf, a vertically slideable door normally closing said opening, a solenoid member connected to said door for raising the same, a concavo-convex oscillatable member mounted adjacent said opening for arresting the bottles rolling down the shelf, means connecting the door and the concavo-convex member and operable by the closing of a circuit to said solenoid member for raising said door and oscillating said concavo-convex member to deliver a bottle through said opening to the exterior of the machine, and means connected to said concavo-convex member and to all of said shafts for simultaneously imparting a partial revolution to the shafts upon oscillation of the concavo-convex member and whereby upon delivery of a bottle through said opening to the exterior of the machine upon oscillation of the concavo-convex member, all of said shafts will be rotated to cause the cams on the shafts on each side of a compartment to release a lowermost bottle in one of the compartments to allow it to fall onto the sloping shelf and to roll against the convex side of said concavo-convex member and to arrest downward movement of a bottle disposed above the released bottle.

16. In a vending machine for bottled beverages, a cabinet, a plurality of spaced partitions in said cabinet and forming compartments into which bottled beverages and the like may be placed in superposed relation, one end of the partitions being at a lower elevation than their other ends, a plurality of rotatable shafts mounted at the lower ends of the partitions and geared together for simultaneous rotation, said cabinet having an opening in one side thereof and a sloping shelf having its lower end coinciding with the lower edge of said opening, said sloping shelf being disposed in spaced relation below the said rotatable shafts, a door for said opening, a solenoid coil connected to said door for raising the same to allow a bottle to roll from said shelf through said opening, means operable upon closing of a circuit for raising said door, a connection between said door and said rotatable shafts to impart simultaneous rotation to all of the shafts upon raising of the said door, each of said shafts having cams thereon and the cams being pitched at different angles on each of the shafts, said cams being arranged to support a column of bottles in each of said compartments and upon a partial rotation of all of the cams, the shafts on one of the cams permitting a bottle to drop from a compartment and the cams on an adjacent shaft engaging the bottle thereabove for preventing its downward movement and whereby a bottle previously released from a compartment will roll out of the compartment while the door is in raised position.

17. In a vending machine comprising a cabinet having a plurality of spaced partitions therein forming a plurality of compartments into which articles may be placed in superposed relation in a horizontal position, a plurality of shafts mounted at the lower end of said compartments and being in alignment with said partitions and each shaft having a pair of cams thereon for supporting and releasing the articles in the compartment, all of said shafts being geared together for simultaneous rotation, means on the exterior of the cabinet and connected to said shafts for imparting a simultaneous rotation to the same to impart a partial rotation to all of the shafts to thus allow the cams on one shaft to release the lowermost article in one of the compartments while the

15

cams on an adjacent shaft on the other side of the compartment move below the bottle about to be released, for supporting the same, and means for directing a released bottle to roll towards the exterior of the machine.

18. In a vending machine having a plurality of compartments formed by a plurality of spaced partitions disposed within a suitable cabinet, a plurality of rotatable shafts, there being a shaft mounted adjacent each side of each of the lowermost end of each of the compartments, means connecting all of the shafts together for simultaneous rotation, said cabinet having a sloping shelf and an opening therein through which articles are adapted to be delivered, the articles being adapted to be stacked in succeeding higher levels in said compartments, each of said shafts having cam means thereon for preventing downward movement of the articles disposed within the compartment, but upon rotation of all of the 10 shafts, the cams on one of the shafts serving to

10

15

20

16

release the lowermost article in one of the compartments and the cams on an adjacent shaft also passing below the next lowermost article in that compartment to prevent its falling from the compartment, and means connected to all of said shafts for imparting simultaneously a partial rotation thereto.
